(57) **CLAIM**

The ornamental design for an absorbent article, as shown and described.

DESCRIPTION

The sole FIGURE is a top plan view of an absorbent article, showing our new design.

The broken lines illustrate portions of the absorbent article and form no part of the claimed design.

The claim lines are directed only to surface ornamentation on a flat surface. The surfaces themselves form no part of the claimed design.

The present industrial design comprises a flat circuit shaped figure, starting at the top of the absorbent article, in heart shape.
